UNITED STATES PATENT OFFICE

OSWIN NITZSCHKE, OF LEVERKUSEN-ON-THE-RHINE, ERICH NOACK, OF WIESDORF-ON-THE-RHINE, AND LEO SCHLECHT, OF LUDWIGSHAFEN-ON-THE-RHINE, GERMANY, ASSIGNORS TO I. G. FARBEINDUSTRIE AKTIENGESELLSCHAFT, OF FRANKFORT-ON-THE-MAIN, GERMANY

MANUFACTURE OF HYDROGEN PEROXIDE

No Drawing. Application filed June 21, 1930, Serial No. 287,347, and in Germany July 13, 1927.

The present invention relates to an improvement in the manufacture of hydrogen peroxide by cathodic reduction of oxygen, more particularly it relates to a process in which the same current of oxygen or of the oxygen-containing gas, required for the working of the electrolytic cell, is used for the concentration or distillation of the hydrogen peroxide solution produced in the electrolytic cell.

In the manufacture of hydrogen peroxide by cathodic reduction of oxygen a vigorous stream of oxygen or of an oxygen-containing gas is passed through the cathode space of the electrolysis vessel. Since only a small fraction of the same is consumed in the reduction, the oxygen or the oxygen-containing gas must be pumped back again in the technical application of the process. Moreover, the hydrogen peroxide solutions produced by electrolysis, which are usually very dilute, must be concentrated and distilled. The pumping back and especially the concentration of the dilute solutions involve considerable expenses.

In accordance with the present invention the cost of concentrating is considerably reduced, if the current of oxygen or of the oxygen-containing gas required to produce a thorough stirring in the electrolytic cell is utilized in the manner known per se for the concentration or distillation of the hydrogen peroxide solutions produced in the electrolytic cell. This can be carried out in various ways. The concentration can be effected in the electrolysis vessel during the electrolysis by drying the oxygen or the oxygen-containing gas or at any rate taking precautions that it reaches the electrolytic cell containing less water than corresponds to the degree of saturation at the temperature of the electrolytic cell. It is however more advantageous to carry out the electrolysis and concentration and especially the distillation in separate apparatus, since in this manner a much higher average current efficiency can be attained, which may amount to 100 per cent. This may likewise be carried out in various manners. It may be of

apparatus or in parts thereof, a higher temperature than in the electrolysis apparatus, in which case the oxygen or the oxygen-containing gas is cooled before entering the electrolytic cell to the temperature of the latter. By working, for example, in such a manner that the temperature in an electrolytic cell amounts to 13° C. and more than 35° C. in the evaporation apparatus (consisting of a trickling tower, which can be heated) and that the current of gas is cooled to 13° C. after leaving the trickling tower, the quantity of gas necessary for stirring suffices to concentrate a one per cent. hydrogen peroxide solution, flowing continually from the electrolytic cell, to a 30 per cent solution. Another practicable mode of working consists in keeping the temperature in the electrolysis and concentration apparatus, at least in parts thereof, substantially uniform, in which case the oxygen or oxygen-containing gas, for example air, is dried before entering the concentration vessel. In this manner, for example, it is possible to concentrate a certain quantity of a one percent solution produced in the electrolysis vessel to 30% by the stream of oxygen needed for its production. Finally it may be advantageous to work in such a manner that the water evaporating in the concentration apparatus is condensed in the suitably cooled electrolysis apparatus. With this mode of execution the constant replenishing of the cathode liquor required for continuous working becomes to a large extent automatic. It thus will be unnecessary to condense the water evaporated in the concentration apparatus in a special separating apparatus in order to lead it back to the cathode space. When it is intended to free the hydrogen peroxide solution obtained in this process from the electrolyte by distillation or to purify the same in any other manner, the working is carried out, for example, in the following manner:

The dried current of oxygen is introduced into a trickling tower and brought into contact with an already concentrated solution of hydrogen peroxide, possessing a considerable hydrogen peroxide partial pressure.

The current of gas leaving the tower laden with water and hydrogen peroxide vapors is then cooled in a condensation vessel, it being advantageous in order to obtain a distillate of the highest possible concentration, to condense only part of the vapors. The gas thus partially dried by cooling is then used again for the further concentration of a dilute solution. By repeated cooling or 10 drying of the oxygen or the oxygen-containing gas in any other appropriate manner, for example, by means of active silicic acid, the production, concentration and distillation of the hydrogen peroxide solution may 15 be carried out simultaneously in a single cycle of operations.

The process thus offers the possibility of producing in a very economical manner and in one process highly concentrated and pure 20 hydrogen peroxide solutions by the cathodic reduction of oxygen.

We claim:

1. In the process for the manufacture of 25 hydrogen peroxide by cathodic reduction of oxygen the step which comprises concentrating the hydrogen peroxide solution produced in the electrolytic cell by passing through it the same current of oxygen which is required for the working of the electrolytic cell.

2. In the process for the manufacture of 30 hydrogen peroxide by cathodic reduction of oxygen the step which comprises concentrating the hydrogen peroxide solution produced 35 in the electrolytic cell by passing through it the same current of oxygen which is required for the working of the electrolytic cell, said concentration or distillation step being carried out in an apparatus separate from the 40 electrolytic cell.

3. In the process for the manufacture of 45 hydrogen peroxide by cathodic reduction of oxygen the steps which comprise concentrating the hydrogen peroxide solution produced in the electrolytic cell by passing through it the same current of oxygen which is required for the working of the electrolytic cell, said concentration or distillation step being carried out in an apparatus separate from the 50 electrolytic cell, and maintaining the evaporation apparatus or parts thereof at a higher temperature than the electrolysis apparatus.

4. In the process for the manufacture of 55 hydrogen peroxide by cathodic reduction of oxygen the steps which comprise concentrating the hydrogen peroxide solution produced in the electrolytic cell by passing through it the same current of oxygen which is required for the working of the electrolytic cell, said 60 concentration or distillation step being carried out in an apparatus separate from the electrolytic cell, maintaining the evaporation apparatus or parts thereof at a higher temperature than the electrolysis apparatus and 65 reducing the temperature of the current of

oxygen to the temperature of the electrolysis apparatus before passing it into the latter.

In testimony whereof we have hereunto set our hands.
